PLASTIC BOAT

Milton M. Siegel, Los Angeles, Calif., assignor to Columbia Plastics Corp., Culver City, Calif., a corporation of California

Filed Oct. 28, 1960, Ser. No. 62,667

Term of patent 14 years

(Cl. D71—1)

FIGURE 1 is a side elevational view of a plastic boat showing my new design;

FIGURE 2 is a top plan view;

FIGURE 3 is a bottom plan view;

FIGURE 4 is a front elevational view;

FIGURE 5 is a sectional view taken along the line 5—5 of FIGURE 2 between the arrows noted;

FIGURE 6 is a sectional view taken along the line 6—6 of FIGURE 2 between the arrows noted; and

FIGURE 7 is a sectional view taken along the line 7—7 of FIGURE 4 between the arrows noted.

The stern of the boat is the same as the prow and the undisclosed side is the same as the side shown.

I claim:

The ornamental design for a plastic boat, substantially as shown and described.
